1 COMBINATION OUTLET

BACKGROUND

The power from the local electric utility must be distributed efficiently to the IT-equipment contained within cabinets in data center facilities (or in enterprise facilities or industrial facilities.) FIG. 1 shows a block diagram of how 3-phase AC power is typically distributed in a data center. The power is typically supplied from a power utility service provider at a high voltage (e.g., 135 kV) and is transformed down to 480 VAC. This power enters the data center facility's main switch gear (along with a backup Diesel generator (D-Gen). The switch gears output is transformed down again (to typically either 208V or 415V) and distributed to Power Distribution Units (PDU) within the data hall. These PDUs distribute power to each of the cabinet in the row of cabinets (utilizing a point-to-point or bus arrangement). Finally, the power entering a cabinet is distributed to each of the IT-equipment within the cabinet, through the Rack Power Distribution Unit (R-PDU). This power is typically distributed in typically 3-phase Delta or Wye configurations to each of the cabinets. The point-to-point or bus method of distribution is described in FIGS. 2A and 2B. The power from the PDU to each of the cabinets (typically in a row) can be bused or routed point to point to the R-PDU. This power distributed to the cabinet (or rack) is then connected to the cabinet's R-PDU where the power is then distributed (in single phase) to each of the IT-equipment contained within the rack (see FIG. 3). The Rack based PDU distributes the power to all the IT-equipment within the rack. The IT-equipment connectivity to the R-PDU utilizes power cords that can have different types of plugs on the ends. The type of plugs/receptacles typically used are defined in IEC 60320. The receptacle at the R-PDU (i.e., female outlets) are typically C13, C15, or C19, while the receptacles (i.e., male outlets) at the IT-equipment side are typically C14, C16, or C20.

It is desirable to have a receptacle within the R-PDU that is multi-purpose (i.e., C13, C15 or C19). This style of receptacle can then accept a C14, C16 or C20 plug on a power cord that typically connects to IT-equipment within the cabinet. This R-PDU receptacle is called a combination outlet and is the subject of this application.

SUMMARY

In a first embodiment, a combination outlet capable of accepting a C14 and C20 plug has a central contact retaining portion and a plurality of tabs surrounding the central contact retaining portion. The tabs are configured to move toward and away from a center of the central contact retaining portion such that the tabs engage an inner surface of a housing of the C20 plug and an exterior surface of a housing of the C14 plug.

In a second embodiment, a combination outlet capable of accepting a C14 and C20 plug has a central contact retaining portion and first and second sets of plungers surrounding the central contact retaining portion. The housing of the C14 plug is configured to depress the first set of plungers and engage an inner surface of the second set of plungers and a housing of a C20 plug is configured to depress the second set of plungers and engage an outer surface of the first set of plungers when a C14 or C20 plug is inserted into the housing.

In a third embodiment, a combination outlet capable of accepting a C14 and C20 plug comprising a central contact-

ing retaining portion and a plurality of circular plungers surrounding the central contact retaining portion wherein a housing of a C14 plug is configured to rotate each circular plunger of the plurality of circular plungers in a first direction and engage an inner surface of each circular plunger and a housing of a C20 plug is configured to rotate each circular plunger in a second direction, opposite the first direction, and engage an outer surface of each circular plunger when a C14 or C20 plug is inserted into the combination outlet.

FIGS. 13A and 13B shows the circular plunger assembly that automatically aligns and restrains either a C14 or C20 plug into the combination outlet.

DETAILED DESCRIPTION OF THE INVENTION

The R-PDU has a significant number of outlets that serve the IT-equipment located within the rack or cabinet. There are typically two types of power connectors that are typically used for connecting IT-equipment to the R-PDU (see FIGS. 4A and 4B). The C13 and C19 receptacles are typically located on the R-PDU and the C14 and C20 receptacles are typically located on the client IT-equipment side. The power cords will hence have a C14/C20 plug end (targeted for the R-PDU) and a C13/C19 plug end (for the client IT-equipment side outlets).

FIGS. 5A and 5B show the first concept of a combination outlet that can accept C14 or C20 plugs. A PDU power combination outlet is shown that can accept multiple types of plugs (e.g., C14 and C20). FIG. 5A shows the C13/C19 combination receptacle on the R-PDU. FIG. 5B shows the

combination outlet with moveable tabs surrounding a central contact retaining portion, the tabs assist in aligning and restraining the plug connectors. When a C20 plug is inserted into the combination outlet the alignment/retainment tabs contact the inner surface of the C20 plug housing. When a C14 plug is inserted into the combination outlet the alignment/retainment tabs contact the outer surface of the C14 plug housing. The tabs have two purposes, first to help align the plugs into the outlet and secondly to help retain or restrain the plug in the outlet and not require a locking component. Since it is desirable that the outlet supply a secure fit with the surrounding housing of the C14 or C20 plug, alignment tabs that make contact with either the inside or outside of this housing are provided. These alignment tabs can be manually placed or automatically placed, see FIGS. 6A, 6B, 6C, 7, 8A, 8B and 8C.

As shown in FIGS. 6A, 6B and 6C, in order to align either a C14 or C20 plug into the combination outlet, alignment tabs are used. FIGS. 6A, 6B and 6C show techniques to align either a C14 or C20 plug into the combination outlet. FIG. 6A shows how the tabs align and restrains the inside wall of the C20 plug while FIG. 6B shows how the tabs align and restrains the outside wall of the C14 plug. FIG. 6C shows a top down view of the combination outlet including the alignment/restraining tabs. In this implementation, the tabs would be moved manually to accommodate the C14 or C20 plug. The tabs are mounted such that when either plug is inserted, they will contact the inner/outer wall of the plug with enough force to restrain them.

FIG. 7 shows the dimensions that are required for these alignment tabs.

As shown in FIGS. 8A, 8B and 8C, in order to align either a C14 or C20 plug into the combination outlet, alignment tabs under a spring force are utilized. FIG. 8A shows how the tabs align and restrains the inside wall of the C20 plug while FIG. 8B shows how the tabs align and restrains the outside wall of the C14 plug. FIG. 8C shows a top down view of the combination outlet and the alignment/restraining tabs. In this implementation, the tabs would be moved automatically to accommodate the C14 or C20 plug and apply enough force to restrain them in place.

FIGS. 9A, 9B and 9C show a second automatic technique (utilizing vertical plungers surrounding the central contact retaining portion) to align either a C14 or C20 plug into the combination outlet. FIG. 9A shows the combination outlet's plug alignment and restraint assembly. FIG. 9B shows an expanded view of this assembly and how the C14 or C20 plug engages the plungers. FIG. 9C shows an expanded view of a part of the assembly whose role is to stop the alternative

plunger from descending and ensuring that this alternate plunger makes contact to the appropriate plug to help align it and restrain it.

FIGS. 10A and 10B show the vertical plunger's automatic technique to align either a C14 or C20 plug into the combination outlet. FIG. 10A shows the combination outlet's C20 plug alignment and restraint and FIG. 10B shows the combination outlet's C14 plug alignment and restraint.

FIGS. 11A and 11B show an alternative implementation of the concept illustrated in FIGS. 9A, 9B and 9C and 10A and 10B (utilizing a set of collars implementing the vertical plungers) that align and restrain either a C14 or C20 plug into the combination outlet. FIG. 11A shows the combination outlet based on his concept, and FIG. 11B shows an exploded view of this assembly and the parts that accommodate the functionality of this embodiment.

FIGS. 12A and 12B show the third concept for an automatic technique (utilizing a circular plunger) to align either a C14 or C20 plug into the combination outlet. FIG. 12A shows the engagement the circular plunger has with a C20 plug and FIG. 12B shows the engagement the circular plunger has with a C14 plug.

FIGS. 13A, 13B and 13C show the circular plunger assembly that surrounds the central contact retaining portion and automatically aligns and restrains either a C14 or C20 plug into the combination outlet. FIG. 13A shows both a C14 and a C20 plug engaging the circular plunger assembly and how one side of the plunger rotates, and the alternate side engages the plug to guide it and restrain it. FIG. 13B shows another view of the engagement of the C14 and C20 plug to either side of the circular plunger assembly. FIG. 13C shows the circular plunger with a spring to control the rotation back to a normal position.

What is claimed is:

1. A combination outlet capable of accepting a C14 and C20 plug comprising:
a bottom wall;
